UNITED STATES PATENT OFFICE.

FREDERICK N. TROLL, OF BALTIMORE, MARYLAND.

IMPROVEMENT IN CORPSE-COOLERS.

Specification forming part of Letters Patent No. 142,533, dated September 2, 1873; application filed June 25, 1873.

To all whom it may concern:

Be it known that I, FREDERICK N. TROLL, of the city of Baltimore and State of Maryland, have invented a new and Improved Ice-Casket; and I do hereby declare the following to be a full, clear, and exact description of the same, reference being had to the accompanying drawing, forming part of this specification, in which—

Figure 1 is a vertical longitudinal section, and Fig. 2 is a cross-section.

The invention relates to burial-caskets for preserving the bodies of deceased persons until it is convenient for their friends to bury them. It consists in providing between the body-receptacle and casket a pipe-connection through which the air may be exhausted. It consists, also, in applying a rubber lining to the inside of casket and cover to exclude all air from the outside.

In the drawing, A represents a wooden casket, and B the cover, both of which are lined on the inside with rubber to more effectually exclude the air. C is the false bottom, perforated and provided with transverse supports. D is the metallic body-receptacle, which is connected, by a rubber pipe, d, with the casket A. This pipe has a tube, d¹, that passes therethrough, being provided on the outside with a stopper, d².

By this means an air-pump may be employed, and the air entirely exhausted from the body-receptacle after the cover has been fastened down. The quantum of oxygen necessary to putrefaction being thus removed,

and a resupply being prevented by the rubber lining, decomposition is effectually arrested. The ice is made to occupy the space between the casket A and the body-receptacle D, while the water therefrom passes through the perforations in false bottom.

The cover B has a subjacent ice-chamber, b, which has an inlet, b¹, and also water-outlet pipes b², that connect with the apertures d³ of the body-receptacle D. The ice-chamber b comes directly over the breast and stomach of the body—that is to say, over those parts in which decomposition begins.

The proper degree of temperature and the proper supply of oxygen—the two essential conditions of putrefaction—being thus effectually prevented, my casket will preserve the body in a perfect condition until the burial takes place, although that may be deferred for a considerable length of time.

Having thus described my invention, what I claim as new, and desire to secure by Letters Patent, is—

1. A body-receptacle, D, provided with the rubber pipe d, tube d¹, and stopper d², extending through the casket A, so that the air may be exhausted, in the manner described.
2. The casket A and cover B, lined on the inside with rubber to exclude the air, in the manner set forth.

FREDK. N. TROLL.
